UNITED STATES PATENT OFFICE

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

ELECTRIC WEFT DETECTOR FOR LOOMS CONTROLLED BY DROP BOXES

Application filed April 17, 1931. Serial No. 530,917.

This invention relates to improvements in electric weft detectors for drop box looms and it is the general object of the invention to select one of a plurality of circuits which shall be closable by means dependent upon movement of the boxes as they shift toward active or picking position.

In certain classes of looms a pair of drop boxes are employed together with two shuttles which are ordinarily provided with the same general kind of filling, each shuttle being in action for but two picks, after which the other becomes active for two picks only, the cycle of movements of the boxes requiring four picks. When a weft detector is provided for each of the boxes it is possible for both of these mechanisms to indicate weft exhaustion on the same detecting beat of the loom, with the result that the detector of the shuttle moving out of action can give an indication. It is necessary under these conditions to prevent the detector corresponding to the idle shuttle from giving an indication, and it is equally desirable to permit the other detector to control the loom. Accordingly, it is an important object of my present invention to provide a pair of electrical circuits each excitable by one of the detectors when weft exhaustion exists in its corresponding shuttle, together with means dependent upon movement of the boxes, and operative preferably during that part of the shifting of the boxes subsequent to the completion of the detection, to determine which of the two circuits shall control the loom.

It is another object of my invention to provide means for retaining an indication of weft exhaustion during the part of the box movement subsequent to completion of the indication, the retention being of sufficient duration to insure closure of an electric circuit, but terminating prior to complete movement of the boxes so that the detectors may be free to return to normal position. By reason of the latter provision the detector of the idle shuttle will be in non-indicating position.

With these and other objects in view which will appear as the description proceeds, my invention resides in the combination and ar-

rangement of parts hereinafter described and set forth in the claims.

In the accompanying drawings, wherein a convenient embodiment of my invention is set forth,

Fig. 1 is an end elevation of a portion of a loom having my invention applied thereto, the shuttles and boxes being in section,

Fig. 2 is an enlargement of a portion of Fig. 1, the shuttle boxes in both of these figures being shown as moved approximately one-half the amount of the box shift,

Fig. 3 is a top plan view taken in the direction of arrow 3, Fig. 2,

Fig. 4 is a detail vertical section on line 4—4, Fig. 3,

Fig. 5 is a top plan view of one of the retainers or selectors on an enlarged scale,

Fig. 6 is a vertical section on line 6—6 of Fig. 5,

Fig. 7 is an enlarged end elevation of one of the selectors looking in the direction of arrow 7, Fig. 5,

Fig. 8 is a diagrammatic view showing the circuits which are controlled by the detectors, and

Figs. 9, 10 and 11 are diagrammatic views showing the parts in different positions.

Referring to Fig. 1, I have shown a loom frame 10 having a lay 11 on which are mounted upper and lower shuttle boxes 12 and 13, respectively. The boxes are mounted on a lifter rod 14 which is operatively connected at the lower end thereof to a box lever 15. The latter derives movement from any of the well-known means for moving box levers, and as set forth herein is intended to have a four-pick cycle so as to hold the boxes first in raised position for two successive picks, and then in down position for the next two successive picks. Upper and lower shuttles S and S', respectively, are alternately positioned actively with respect to the race 16 of the lay, each shuttle being in action for but two picks at a time.

A feeler stand 20 mounted in fixed position on the loom frame has an upright guideway 21 in which is mounted a slide 22. The latter is formed with upper and lower platforms 23 and 24, respectively, on which are mount-

55

60

100

ed upper and lower detectors 25 and 26. Each detector cooperates with one of the shuttles and is required to move vertically with its box by means of a connector rod 27 which is 5 interposed between the slide 22 and the lever 15. By reason of this connection the boxes and detector shift in unison vertically and as the lay swings forwardly each detector will enter its corresponding shuttle to detect the condition of weft on the bobbins. The shuttles S and S' are shown as provided with weft supplies or bobbins B and B', respectively.

Each of the detector mechanisms comprise 15 a bed 30 and a cap 31 which are held in position by a bolt 32 passing through the corresponding platform. A compression spring 33 lies between the bed and cap, the forward end of the spring bearing against the bed 20 while the rear part bears against a detector 34. The latter is pivotally connected as at 35 to a slide 36 rearward movement of which is limited by an offset 37 which engages the feeler cap. The upper feeler 25 has a rearwardly extending yarn engaging detector arm 38 while the lower detector has a corresponding arm 39, these arms being pivoted on their corresponding slides and acted upon by the springs to be held in detecting position. The 30 arm 38 is provided with a forwardly extending finger 40, while the lower arm has a similar finger 41. Each slide 36 has a stop 42 which limits angular movement of the detector arms and fingers about their pivots.

35 The matter thus far described, except for the form of the fingers 40, forms no part of my present invention, the detectors being of the general type shown in patent to Payne No. 1,738,198 and the detectors and boxes 40 moving in the usual manner.

Because of the fact that each detector can have a side slipping movement on the forward beat of the lay when the shuttles are located at the box end of the loom, it is to be 45 understood that the detector corresponding to the shuttle which is moving out of action can give an indication of weft exhaustion if this condition exists. It is desirable, however, not to use an indication unless it is in connection with the shuttle which is moving into action. My invention relates more particularly to a means for preventing the detector corresponding to the shuttle moving out of action from controlling the loom, and 55 also for insuring that a shuttle which moves toward active position will be in control of the loom.

It is to be understood that the type of detector set forth herein has a side slipping movement due to forward movement of the lay, and the sliding is completed when the lay reaches its extreme forward position. At 60 this time when weft is absent the detectors will be in the dotted line position shown in Fig. 3, the fingers 40 or 41 being spaced from

the caps and beds. I make use of this condition by mechanism which I will now describe.

A retainer or selector, designated generally at 50, may be mounted about a horizontal axis 51 parallel to the lay and shuttles. This axis is carried by a support 52 which is provided with a holding foot 53 bolted to the guide frame 21 by bolt 54. The foot 53 and bolt 54 permit a limited amount of adjustment of the pivot in a direction parallel to the lay. A yielding plunger lock 55 has a head 56 with bevelled faces 57 held in contact with similarly inclined surfaces 58 formed on a retainer and contact carrier 59 by means of a compression spring 60. The latter is interposed between the head and a guide 61 on the support 52. The effect of the head 56 is to hold the member 59 yielding in the position shown in Fig. 2.

The retainer part 59 may be forked to have upper and lower arms 62 and 63, respectively, defining between them a slot 64. The upper arm may be provided with a vertical post 65 to which is secured a contact 66 which does not extend around the entire post but is located on that part of the latter opposite the feeler beds. The contact is held in place by a screw 67 threaded vertically into the post to hold the contact in fixed position, and a binding screw 68 may hold an upper wire 69 in electrical contact with the member 66.

In similar manner the lower arm 63 is provided with a post 70 to which is secured a contact plate 71 held to the post by means of screw 72. A binding screw 73 provides connection for a lower wire 74. Both of these contacts terminate preferably at the horizontal edges and sides of the slot 64.

The lengths of the contacts 66 and 71 form an important part of my present invention and are determined by the amount of vertical movement of the detectors. As shown in full lines in Fig. 2, the boxes and detectors are at an intermediate position, preferably with the boxes half shifted. It is desirable that each detector shall be free to return to the normal full line position shown in Fig. 3 after the boxes have completed their shifting movement, whether the latter be up or down.

Assuming that the weft in both shuttles is exhausted so that both detectors will swing to the dotted line position shown in Fig. 3 when the lay is in its forward position and the boxes approximately half shifted, a description of the operation of the parts will be given in connection with Figs. 2, 9, 10 and 11. Fig. 9 indicates the boxes down and lay moving forwardly just after boxing of the top shuttle S. As the lifter rod rises and the lay continues to move forwardly, the detectors will both engage their bobbins and start to move angularly, being in the position suggested by Fig. 10 with the lay still

behind front center. The bottom feeler is still below contact 71, while the upper detector will move to engage insulated post 65.

As the lay moves to its front position shown in Fig. 2, the upper detector will rise above the post, and the lower detector still below contact 71 will swing to the dotted line position shown in Fig. 3. This positions the lower finger 41 beyond the contact 71 with respect to the corresponding bed and cap, as suggested in Fig. 3. In other words, when the lay is in front center the post 70 and contact 71 will lie between the arm 41 and the corresponding bed 30.

Continued upward movement of the boxes while the detectors are still moved to their extreme angular position will effect contact between arm 41 and contact 71. As the lay moves rearwardly the bottom feeler will leave its bobbin and the corresponding spring 33 will move finger 41 against contact 71. This contact will be preserved throughout the major part of the remainder of the shifting movement of the boxes, but as the latter approach a condition of rest with respect to the lay in upper position the arm 41 will move over the contact 71, to the position shown in Fig. 11. As the lower detector rises above the contact 71 the spring 33 of the lower feeler will swing arm 39 and finger 41 back to normal position. The arm 41 comes to rest in alignment with slot 64 between the contacts 66 and 71 with the boxes fully raised and with the lower box and its shuttle in active position with respect to the lay race 16. This shuttle will therefore be picked to the opposite side of the loom where replenishment or loom stoppage may be effected.

Fig. 8 shows circuits by means of which indication may be made to control the loom. When contact is established between the lower arm 41 and its contact 71, the following circuit is completed: ground G, arm 41, contact 71, wire 74, wire 80, source of electric power P, wire 81, electromagnetic device 82, and wire 83 back to the ground. Current flowing in this circuit will energize the device 82 which in turn will attract its armature 84. Movement of the latter effects a change in the operation of the loom by well-known means. It is not deemed necessary herein to show the mode of control, inasmuch as several well-known devices are available which can produce either replenishment or loom stoppage by the movement of an indicator corresponding to the element 84.

In the conditions just described it is understood that the top arm 40 had no opportunity to engage contact 66, hence it was incapable of closing a circuit. This is a desirable condition because even though the upper box be exhausted under the condition assumed, yet it is not desirable to effect replenishment by a control exercised by the upper box when its

shuttle is to remain on the drop box side of the loom.

In similar manner, if the boxes should be raised at the begining of a shift so that the top box is to be restored to action and the lower box is to be moved out of active position, a relation of parts very similar to that already described will take place, exhaustion in the upper box moving the detector arm corresponding thereto into contacting position with respect to element 66 and as the boxes complete the latter part of their downward shift, a circuit will be closed by the upper detector so that current will flow as follows: ground G, upper detector finger 40, contact 66, wire 69, wire 80, battery or source of power P, wire 81, solenoid or armature 82, wire 83 back to the ground. Energization of this circuit will result in the movement of armature 84 so that a change in the operation of the loom will be brought about when the upper shuttle is brought into action.

It is to be understood that even though the lower detector should indicate exhaustion it will not be able to engage contact 71 because the detectors do not begin to have their angular movement until after the detector of the box moving to idle position is in engaging position relatively to one or the other of the posts. If either detector should have an incomplete movement so that its forwardly projecting arm will be in vertical alignment with one or another of the posts, movement of the boxes will cause a yielding of the retainer due to the action of the spring plunger 55, and after the strain is relieved the inclined faces 57 and 58, together with the spring 60, will act to return the retainers to normal position.

From the foregoing it will be seen that I have provided means for retaining an indication of weft exhaustion which may be given by either feeler and make use of such an indication to complete a loom controlling the circuit during the latter part of the shifting of the boxes, the circuit completed corresponding to the shuttle which is next to be active. It will further be seen that the contacts on the posts are spaced, so that the detector which is in active position will be free to return to normal position, hence, when the exhausted shuttle is replenished and a fresh supply is picked back to the drop box end of the loom, the detector corresponding thereto can move away from action without interference on the part of either of the posts.

Having thus described my invention it will be seen that changes and modifications may be made therein by those skilled in the art without departing from the spirit and scope of the invention and I do not wish to be limited to the details herein disclosed, but what I claim is:

1. In a box loom operating with a lay and a pair of shifting shuttle boxes each of which is in active position for two successive picks and

then in idle position for two picks, an electrical weft detector for each box, the detector moving with the boxes as the latter shift, each detector capable of giving indication of weft exhaustion of the corresponding box when the boxes have completed approximately half their shifting movement, an electric circuit for each detector, an electro-magnetic device common to the circuits and capable of causing a change in the operation of the loom, means operative during the latter part of the shifting movement of the boxes to retain the indication of either detector and act to close the circuit of the detector corresponding to the box moving into active position.

2. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, and means to retain an indication given by the detector corresponding to the box moving into active position and close the circuit of such detector during the latter part of the shifting of the boxes.

3. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, a retainer for each detector located to retain an indication of weft exhaustion given by the detector of a box moving toward active position, the detector of the other box moving away from its retainer, and means effective during the latter part of the shifting of the boxes to close the circuit corresponding to the box moving to active position due to the retaining of the corresponding detector in indicating position.

4. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, means to retain the indication

of only one detector, the one corresponding to the box moving to active position, and means dependent upon retaining the indication to close the circuit corresponding to the box moving toward active position.

5. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, and means dependent upon the direction of shifting of the boxes to retain the indication of that detector corresponding to the box moving toward active position, and means operative during retention of the retained indication to close the circuit corresponding to the box moving toward active position.

6. In a loom having a lay and two shifting shuttle boxes which shift every other pick of the loom relatively to active position when occupied by their shuttles, a weft detector for shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, and an indication retainer for each detector, said retainers being operative one only at a time, the operative one corresponding to the box moving into active position, the retainer being operative during the latter part of the shifting of the boxes.

7. In a loom having a lay and two shifting shuttle boxes which shift every other pick of the loom relatively to active position when occupied by their shuttles, a weft detector for and shifting each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, and an indication retainer for each detector, each retainer being brought into cooperative relation with the corresponding detector when the latter has indicated weft exhaustion and during the second half of the shifting movement of the shuttle boxes.

8. In a loom having a lay and two shifting shuttle boxes which shift every other pick of the loom relatively to active position when occupied by their shuttles, a weft detector for and shifting with each box, an electric circuit for each detector, a loom controlling elec-

5 electromagnetic device common to the circuits, each detector capable of indicating weft exhaustion when the boxes are partly shifted and capable when indicating weft exhaustion of closing the circuit corresponding thereto, and selector means acting to prevent closure of either circuit until the boxes have completed more than half of their shifting movement, the selector coacting with movement of the boxes to render operative the circuit corresponding to the box moving toward active position.

10 9. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, a pair of indication retainers each to hold the corresponding detector in weft exhaustion indicating position, said retainers having retaining relations alternately with respect to their corresponding detectors and dependent upon the direction of shifting of the boxes to determine which retainer shall be operatively related to its detector.

15 10. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, means dependent upon the direction of shifting of the boxes and operative during the latter part of the shifting movement to boxes to close the circuit corresponding to the box next to become active when both detectors indicate weft exhaustion.

20 11. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion during shifting of the boxes and capable when indicating weft exhaustion of closing the circuit corresponding thereto, means to retain the weft detector corresponding to the box moving to active position in indicating circuit closing position when weft

25 exhaustion exists in the corresponding box during the latter part of the shifting movement of the boxes, said means releasing the detector near the end of the shifting movement of the boxes.

30 12. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, means to coact with the detector corresponding to the box moving into action after said detector has had a complete indicating movement to hold said detector in indicating position to close the circuit corresponding thereto during the greater part of the remaining shifting movement of the boxes, the means releasing the detector near the end of the shifting movement.

35 13. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, and a pair of electrically separate contacts, one for each detector, said contacts positioned so that but one of them is electrically connected to its detector at a time dependent upon the direction of shift of the boxes, each contact operative during the latter part only of the shifting movement of the boxes when the corresponding detector indicates weft exhaustion.

40 14. In a loom having a lay and two shifting shuttle boxes which shift every other pick of the loom relatively to active position when occupied by their shuttles, a weft detector for and shifting with each box, an electric circuit for each detector, a loom controlling electromagnetic device common to the circuits, each detector capable of indicating weft exhaustion when the boxes are partly shifted and capable when indicating weft exhaustion of closing the circuit corresponding thereto, a pair of electrically insulated contacts located adjacent the shuttle box in active position, each contact to have electrical engagement with the corresponding detector when the latter indicates weft exhaustion, the detector of the box moving into active position being electrically relatable to the corresponding contact if weft exhaustion exists
